UNITED STATES PATENT OFFICE

VICTOR P. WEIDNER, OF PORT WASHINGTON, NEW YORK

DESIGN FOR A DISPLAY CABINET FOR BULLETIN PRINTERS

Application filed January 14, 1932. Serial No. 42,472. Term of patent 7 years.

To all whom it may concern:

Be it known that I, VICTOR P. WEIDNER, a citizen of the United States, residing at Port Washington, in the county of Nassau and State of New York, have invented the new, original, and ornamental Design for a Display Cabinet for Bulletin Printers, of which the following is a specification, reference being had to the accompanying drawing, forming a part thereof.

The single figure is a perspective view showing my design of a display cabinet for

bulletin printers in which A designates the casing of the cabinet, B indicates a transparent window therein, and C indicates a strip of material such as paper for receiving a printed impression.

I claim:

The ornamental design for a display cabinet for bulletin printers as shown and described.

In testimony whereof, I affix my signature.

VICTOR P. WEIDNER.
